UNITED STATES PATENT OFFICE.

SEIKICHI KARIYA, OF PORTLAND, OREGON.

NON-REFILLABLE BOTTLE.

1,293,464.

Specification of Letters Patent.

Patented Feb. 4, 1919.

Application filed January 9, 1918. Serial No. 211,013.

To all whom it may concern:

Be it known that I, SEIKICHI KARIYA, a subject of the Emperor of Japan, residing at Portland, in the county of Multnomah and State of Oregon, have invented new and useful Improvements in Non-Refillable Bottles, of which the following is a specification.

This invention relates to improvements in non-reusable bottles, the object of the invention being to provide simple, reliable and efficient means for indicating initially that no portion of the contents of the bottle has been discharged, and for indicating thereafter that a portion of the contents of the bottle has been discharged, thus guarding the intending purchaser of a bottle of liquid against the purchase of a bottle of liquid which has been partially or wholly emptied of its original contents and refilled.

A further object of the invention is to provide a novel type of valve mechanism for the purpose described, which will serve as an initial closure to prevent escape of the contents of the bottle, and which may be adjusted to permit of the discharge of the contents of the bottle and which will then serve as means for indicating that the bottle has been initially filled and opened.

The invention consists of the features of construction, combination and arrangement of parts, hereinafter fully described and claimed, reference being had to the accompanying drawing, in which:

Figure 1 is a vertical longitudinal section through the neck of a bottle embodying my invention, showing the valve or stopper in normal position and serving as a seal.

Fig. 2 is a view similar to Fig. 1 showing the valve or stopper in the process of being forced downward from a sealing to an indicating position.

Fig. 3 is a horizontal transverse section on the line 3—3 of Fig. 1.

Fig. 4 is a horizontal transverse section on the line 4—4 of Fig. 2.

Referring to the drawing, 1 designates the body of a bottle having an abbreviated or shortened neck portion 2 formed with a reduced extension 3. The neck portion 2 is designed to be completed by the application of a primarily independent cap 4, preferably made, like the bottle, of glass or other suitable transparent or translucent material. This cap 4 is provided with a top wall 5 having a constricted opening 6 therein,

and said cap portion fits at its lower end about the reduced extension 3 and is adapted to be secured thereto in any suitable manner. In the present instance I have shown the extension 3 and cap portion formed with grooves in their meeting faces to receive a filler 7 of cement or other suitable material, whereby the cap is secured in place and can not be removed without either breaking or otherwise mutilating the bottle or cap in such a manner as to indicate that the bottle has been tampered with.

The cap 4 serves as an inclosing casing for an interior valve shell 8, also preferably made of glass or other suitable transparent or translucent material. This valve shell snugly fits the interior of the cap and is in the form of a tapered tube provided between its center and upper end with an interior annular shoulder 9 forming a passage 10 and sub-dividing the interior of said shell into an upper sealing chamber 11 and a lower runway or receiving chamber 12, said chambers being in communication through 80 the passage 10.

Interposed between the lower edge of the shell and the upper edge of the neck portion 3 is a washer or gasket 13 provided with an opening 14, and interposed between the upper edge of the shell and the wall 5 of the cap is a similar washer or gasket 15 having an opening 16. These openings 14 and 16 are of somewhat restricted diameter, but of sufficient diameter to permit of the free outflow of the liquid when the bottle is in condition for the liquid to be discharged. In practice, the opening 16 is preferably made of the same size as the opening 6, and the washers 13 and 15 are made of cork or other suitable elastic material and serve to hold or bind the valve shell in position against movement and to also seal the interior joints against the leakage of liquid.

A valve or stopper 17, preferably of the ball type, is provided for initially sealing the bottle and to serve as an indicator after the bottle is initially unsealed. This valve or stopper is designed to be initially placed in the chamber 11 to seal the openings 6 and 16 against the escape of the contents of the bottle, and when in such position said valve or stopper rests against an elastic seat and guard ring 18 disposed within the chamber 11 and resting upon the upper surface 110 of the shoulder 9. After the bottle has been originally filled, the valve shell and washer

13 are placed in position with the ring 18 and stopper 17 disposed in the chamber 11, after which the washer 15 is fitted in position and the cap 4 applied and secured in place to confine the valve shell and contained parts in a permanent manner. The stopper 17 will thereupon be held by the elasticity of the ring 18 in position to close the passage 10 and opening 16 to seal the bottle against the discharge of liquid, in which position the stopper also indicates the fact that the bottle has been filled but once and that no portion of its contents has as yet been discharged. In order to break this seal, a form of tool is provided consisting of a stem 19 having a handle 20, which stem is inserted through the openings 6 and 16 and arranged to bear against the stopper 17, which, by the application of proper pressure, is forced downward through the ring 18 into the chamber 12, the ring 18 expanding to allow the stopper to pass and then contracting to prevent its return to the chamber 11. The bottle will then be sealed for the discharge of its contents as desired, in which operation the stopper 17 will roll back and forth in the chamber 12, being limited in outward movement by contact with the shoulder 9, so that by tilting or canting the bottle the liquid may be discharged. The chamber 12 is of sufficiently larger diameter than the stopper 17 to permit the liquid to freely flow past the same, but if desired said chamber may be provided with a series of longitudinal grooves 21 to allow the liquid to run freely past the stopper in any position of the latter. When the bottle is disposed in a vertical position, the stopper 17 rests upon the bottom washer 13 and may close the opening 14, but if desired any suitable form of stopper may be inserted in the openings 6 and 16 to close the bottle against the access of dust, dirt and other foreign substances.

It will thus be understood that after the bottle has been filled the stopper 17 will act as a closure, but that when this closure is once depressed into the chamber 12 it can not return to its normal sealing position, and therefore the contents of the bottle may be as freely discharged as desired. As, however, the stopper will remain in the chamber 12, it will indicate to anyone familiar with the type of bottle that the bottle has been initially unsealed, thus warning the intending purchaser of a bottle of liquid of that fact, thus safe-guarding the public against the purchase of a bottle which has been refilled with liquid or from which a portion of the original contents has been drawn.

It will be observed that the shoulder 9 is provided with a downwardly and inwardly inclined upper surface or seat for the elastic ring 18, and that the said ring 18 is of cir-

cular form in cross section. By this construction of the shoulder and the ring any possible displacement of the ring in a downward direction is avoided, while the inclined face of the shoulder permits the ring to spread vertically under downward forcing pressure of the valve 17, in which action the cross sectional contour of the ring, as shown in Fig. 2, various from circular to oval or elliptical form, the sides of the ring thus being lengthened in a vertical direction as the ring spreads. Hence, while the valve will be normally supported by the ring in a tight sealing condition against the ingress of dust, dirt or other foreign substances, pressure upon the ring of a certain degree will permit the valve to be forced downwardly into the runway 12, the elastic ring thereafter contracting and resuming its normal shape to form a seat for the movable valve 17. By the use of a ring of the form described further substantial advantages are gained over a ring of angular form in cross section, in that the circular ring may be made of low grade rubber and yet adapted to have great elasticity, on account of its less resistance to expansion and contraction.

While the construction disclosed is preferred, it will, of course, be understood that changes involving claims may be made without departing from the spirit of the invention or sacrificing any of the advantages thereof.

Having thus fully described my invention, I claim:

1. A bottle having a fluid discharge passage, including superposed chambers connected by a constricted passage, said passage defining an annular shoulder having an upper surface inclined downwardly and inwardly toward said passage, the said upper chamber communicating with the final outlet and the lower chamber with the interior of the bottle, an inelastic vertical stopper disposed within the upper chamber to seal said constricted passage and the final outlet, and an elastic ring of circular form in cross section resting upon the inclined upper face of the shoulder, said ring forming a seat for normally holding said stopper in sealing position, said ring adapted to be expanded from a cross sectional circular to a cross sectional elliptical form under pressure upon the stopper, whereby said stopper may be freely forced downwardly through the ring and constricted passage into the lower chamber.

2. A bottle having a shortened neck portion, a cap permanently secured thereto and provided with a final outlet, a valve shell enclosed by the cap and provided with an interior shoulder forming upper and lower chambers and a constricted intervening passage, said shoulder having a downwardly and inwardly inclined upper surface, the

upper chamber communicating with said final outlet and the lower chamber with the bottle neck, an elastic ring cross-sectionally of circular form confined within the upper 5 chamber above said constricted passage and resting upon the inclined upper face of said shoulder, an inelastic spherical stopper adapted to be disposed in the upper chamber and held by the elastic ring in position 10 to close the final outlet, and adapted to be forced downward through said ring into the lower chamber, and means for holding the valve shell in position within the cap.

3. A bottle having a shortened neck portion, a cap permanently secured thereto and provided with a final outlet, a valve shell enclosed by the cap and provided with an interior shoulder forming upper and lower 15

chambers and a constricted intervening passage, the upper chamber communicating 20 with said final outlet and the lower chamber with the bottle neck, an elastic ring confined within the upper chamber above said constricted passage, a spherical stopper adapted to be disposed in the upper chamber and 25 held by the elastic ring in position to close the final outlet, and adapted to be forced downward through said ring into the lower chamber, and elastic washers disposed between the lower edge of the shell and the 30 edge of the neck and between the upper edge of the shell and crown wall of the cap, respectively.

In testimony whereof I affix my signature.

SEIKICHI KARIYA.
